VEHICLE LAMP LENS

Robert I. Nagel, Skokie, Ill., assignor to R. E. Dietz Company, Syracuse, N.Y., a corporation of New York

Filed Oct. 19, 1965, Ser. No. 87,587

Term of patent 14 years

(Cl. D48—32)

FIG. 1

FIG. 2

FIG. 3

FIGURE 1 is a top plan view of a vehicle lamp lens embodying my new design, it being understood that the prisms seen through the lens in the segmental-rectangular areas on opposite sides of the square center area, and which prisms are partially shown in said opposite side areas, continue uniformly throughout said opposite side areas;

FIGURE 2 is a side elevational view thereof, it being understood that the diffusion ridges seen through the sides and ends of the lens, and which are partially shown along said sides and ends, continue uniformly along said sides and ends; and

FIGURE 3 is an end elevational view thereof.

I claim:

The ornamental design for a vehicle lamp lens, substantially as shown.
